CANDLE LAMP

William F. Meara, Oak Park, Ill., assignor to Bloomfield Industries, Inc., Chicago, Ill., a corporation of Illinois

Application February 4, 1953, Serial No. 23,441

Term of patent 14 years

(Cl. D48—2)

To all whom it may concern:

Be it known that I, William F. Meara, a citizen of the United States, and a resident of Oak Park, in the county of Cook and State of Illinois, have invented a new, original, and ornamental Design for a Candle Lamp, of which the following is a specification, reference being had to the accompanying drawing forming a part thereof, and in which:

Fig. 1 is a front elevational view of a candle lamp, showing my new design; and

Fig. 2 is a top plan view thereof, the broken lines indicating a shade being omitted for convenience of illustration. The dominant features of my design are shown in solid lines.

I claim:

The ornamental design for a candle lamp, as shown and described.

WILLIAM F. MEARA.
